UNITED STATES PATENT OFFICE.

RUDOLPH JARY, OF CHICAGO, ILLINOIS.

AEROPLANE.

1,071,425.

Specification of Letters Patent. Patented Aug. 26, 1913.

Application filed February 25, 1913. Serial No. 750,543.

To all whom it may concern:

Be it known that I, RUDOLPH JARY, a former subject of the King of Austria-Hungary, but who have declared my intention of becoming a citizen of the United States, and a resident of the city of Chicago, county of Cook, and State of Illinois, have invented certain new and useful Improvements in Aeroplanes, of which the following is a specification.

My invention relates to aeroplanes and the object of this improvement is to provide an aeroplane which is adapted to carry a number of persons and in which a plurality of supporting planes is furnished, certain of which planes are adapted to be removed when not needed.

A further object is to produce a simple and effective device of the character mentioned. Other objects will appear hereinafter.

The invention consists in the combinations and arrangements of parts herein-after described and claimed.

25 The invention will be best understood by reference to the accompanying drawings forming a part of this specification, and in which,

Figure 1 is a plan view of an aeroplane embodying my invention, Fig. 2, a front elevation of the same, Fig. 3, a side view of the same, and Fig. 4, an enlarged fragmental section illustrating the means for attaching the removable planes.

35 The preferred form of construction as illustrated in the drawings comprises a frame 5 in which is operatively mounted a motor 6 adapted to drive the propeller 7. Said frame 5 is provided with wheels 40 adapted for use in alighting and starting the aeroplane. The aeroplane is also provided with a conventional steering rudder 9 and elevating rudder 10. Said elevating and steering mechanisms may be of any 45 preferred or conventional design and operated in the conventional or any desired manner. The controlling wires 11 running from said rudder and elevating plane extend into convenient position to the operator in the ordinary manner. The frame

50 work, motor, propeller, rudder and elevating planes are such as are already in common use but my invention relates to the supporting planes and the car adapted to carry passengers and the like. The supporting planes are arranged as in the bi-

plane type. I arrange two upper supporting planes 12 on the frame 5 and space them apart sufficiently far to insert a third supporting plane 13 which is preferably in two sections, divided in the center and extended beyond the ends of said planes 12 substantially as indicated. Immediately beneath the upper supporting planes 12, are lower supporting planes 14 which are also spaced apart substantially as shown. The supporting planes 13 are adapted to be removed when not needed, by removing the bolts 15 which are shown in detail in Fig. 4. The use of the removable supporting planes 13 will only be necessary when greater weights are carried, the supporting planes 12 and 14 being sufficient when lesser weights are carried.

55 Suspended from the frame 5 is an in-closed car 16 having windows 17 and a door 18 through which freight or passengers may be passed. Depended from the car 16 are supporting wheels 19 adapted to support the car and aeroplane when the device is on the ground and to facilitate starting and alighting. The forward portion of the car 16 is provided with an opening substantially as indicated at 20 in Fig. 1 through which the operator enters the operator's compartment 21. The compartment 21 is provided with a seat 22 for use by the operator and the controlling and operating mechanisms of the aeroplane, not shown, are positioned in the compartment 21 in any preferred or conventional manner. The compartment 21 is preferably formed entirely of a transparent substance so that the operator's vision will not be impaired.

65 While I have illustrated and described the preferred form of construction for carrying my invention into effect, this is capable of variation and modification without departing from the spirit of the invention. I, therefore, do not wish to be limited to the exact details of construction set forth, but desire to avail myself of such variations and modifications as come within the scope of the appended claims.

Having described my invention what I claim as new and desire to secure by Letters Patent is:

75 1. An aeroplane comprising a frame; two laterally disposed upper supporting planes spaced apart in a substantially horizontal plane in said frame; removable supporting planes between said spaced supporting

planes with their outer ends extending beyond the outer ends of said supporting planes; means removably securing the lateral edges of said removable supporting planes to adjacent edges of said spaced supporting planes; and lower supporting planes in said frame positioned under said spaced upper supporting planes, substantially as described.

10 2. An aeroplane comprising a frame; two laterally disposed upper supporting planes spaced apart in a substantially horizontal plane in said frame; removable supporting planes between said spaced supporting planes having their adjacent ends spaced apart and their outer ends extended be-

yond the outer ends of said spaced supporting planes; bolts in the edges of said spaced supporting planes and said removable supporting planes removably securing the lateral edges of the latter with adjacent edges of the frame; and lower supporting planes in said frame directly under said upper spaced supporting planes, substantially as described.

25

In testimony whereof I have signed my name to this specification in the presence of two subscribing witnesses.

RUDOLPH JARY.
